DESIGN FOR AN ILLUMINABLE BUBBLING DEVICE OR THE LIKE

John Petry, New York, N. Y., assignor to Raylite
Electric Corporation, Bronx, N. Y., a corpora-
tion of New York

Application December 7, 1946, Serial No. 135,338

Term of patent 14 years

(Cl. D26—8)

To all whom it may concern:

Be it known that John Petry, a citizen of the United States and resident of New York city, in the county of Queens, State of New York, has invented a new, original, and ornamental Design for an Illuminable Bubbling Device or the like, of which the following is a specification, reference being had to the accompanying drawing, forming part thereof, in which Fig. 1 is a front elevational view of an illuminable bubbling device showing my new design and Figs. 2 and 3 are top plan and bottom views, respectively, thereof.

I claim:

The ornamental design for an illuminable bubbling device or the like, as shown.

JOHN PETRY.
